JOHN R. ROGERS, OF BROOKLYN, NEW YORK.

INTERNAL-COMBUSTION ENGINE.

1,189,872.

Specification of Letters Patent.

Patented July 4, 1916.

Application filed July 9, 1910. Serial No. 571,142.

To all whom it may concern:

Be it known that I, JOHN R. ROGERS, a citizen of the United States, residing in the borough of Brooklyn, county of Kings, and State of New York, have invented certain new and useful Improvements in Internal-Combustion Engines, of which the following is a specification.

My invention relates to internal combustion engines, and the object is to provide an engine of the two cycle or two phase type which shall be simple in construction and which shall provide a more certain means of obtaining a regular and efficient action of the engine. One means of attaining this object is secured by a certain scavenging of air previous to the introduction of the explosive charge and consists in certain arrangements and relations of the parts to accomplish this object as will be herein-after described.

Other objects and advantages will appear from the following description taken in connection with the accompanying drawings which illustrate one means of carrying out my invention.

I have shown my invention as applied in a form adapted for use especially in connection with an automobile or a motor boat, but it can be applied to other purposes without change of the principle involved.

In the drawings Figure 1 is a vertical sectional view through the center of the cylinder and the crank case of an engine constructed according to my invention, showing the parts when the explosive charge is compressed and ready to be exploded. Fig. 2 is a view similar to Fig. 1, showing the working pistons near the lower end of their movement, the left hand working piston having reached its extreme downward movement and the right hand working piston approaching the end of its movement. Fig. 3 is a similar view to Fig. 1, showing the left hand working piston beginning its return and the right hand working piston having reached the extreme limit of its movement. Fig. 4 is a transverse sectional view along line 4-4 of Fig. 1. Fig. 5 is a transverse sectional view along line 5-5 of Fig. 1. Fig. 6 is a transverse sectional view on an enlarged scale of one of the stationary pistons along the line 6-6 of Fig. 3; and

Fig. 7 is a vertical sectional view along line 7-7 of Fig. 6.

Similar letters of reference indicate similar parts throughout the several views.

A, A' indicate twin cylinders formed of a single casting, the cylinders being separated from each other by a wall B and having a common explosion chamber C at the upper end of the cylinders.

D represents a crank case on which the cylinders A, A' are supported and to which they are fastened by any suitable means, such as bolts D' D'.

The cylinder casting is provided with water chambers E, E in its walls and the wall B is provided with suitable water chambers E', E'. The cylinders A, A' are offset with relation to the crank shaft F in order to obtain a differential motion of the working pistons G, G'. Working piston G and G' are connected by means of suitable cross-heads with connecting-rods H and H' mounted on pin I on crank J on the main shaft F. Within working pistons G, G' are mounted stationary pistons K, K' supported by conduits or pipes L, L, L, L, and L', L', L', L' respectively, the conduits or pipes L and L' being mounted in the base plate D² of crank case D. The stationary pistons K and K' are adjustable with relation to their supporting conduits or pipes so as to increase or decrease the size of the compression chambers M, M' formed between the top of working pistons G, G' and stationary pistons K, K', such adjustment being attained by means of suitable adjusting nuts N adapted to clamp fixed pistons K, K' to the conduits or pipes L, L' respectively, as is clearly shown in Fig. 6.

In base plate D² of crank case D are cast passages D³ and D⁴ which communicate respectively with conduits or pipes L and L'. Passage D³ connects with a pipe O forming the air inlet controlled by an ordinary check valve O'. Passage D⁴ connects with a pipe O² communicating with the carburetor and controlled by an ordinary check valve O³. The conduits or pipes L and L' and the passages D³ and D⁴ are duplicates of each other and arranged on opposite sides of the base plate as shown. The heads G² and G³ of the working pistons G and G' are screwed into the ends of the working pistons and

each of them is provided with an air chamber as shown.

The cross-heads for connecting-rods H and H' with working pistons G and G' are mounted in the lower part of pistons G and G' in the usual manner and in such a position that they do not interfere with the conduits or pipes L, L'.

P is a chamber in the wall of the left hand cylinder to act as an exhaust chamber and is connected by a pipe P' to a muffler (not shown) or to the open air.

P² is a circumferential slot forming a means of communication between cylinder A and exhaust chamber P. In the wall B, between cylinder A and A' is cast a passage Q forming a means of communication between the two cylinders A and A'. In working piston G there is a port or opening R adapted to register at the lower end of the stroke with one end of the passage Q so that the contents of the compression chamber M may pass at that time to the right hand cylinder A'. In the wall of the right hand cylinder is formed a passage R' and in the wall of working piston G' there is a port or opening R² adapted to register at the lower end of the stroke with the lower end of passage R' so that the contents of the compression chamber M' may pass over head G³ of working piston G' and into explosion chamber C as is clearly shown in Fig. 3.

S is a spark plug of any suitable construction, T the water inlet for the water jacket or chamber in the walls of the cylinders and T' the water outlet for the same.

The operation of the device is as follows: A charge being previously introduced and compressed in explosion chamber C is fired in the usual way by the spark plug S. Both working pistons G and G' descend under the force of the explosion until working piston G passes the slot P² communicating with the exhaust chamber P allowing the contents of both cylinders to exhaust into chamber P and thence through pipe P'. The opening P² between exhaust chamber P and the interior of the cylinders is of considerable size, and circumferential with relation to the cylinders. Due to the size of this opening into exhaust chamber P the descent of working piston G uncovers the same very rapidly before the port R in said piston registers with passage Q. The burnt gases in both cylinders therefore will escape to a large extent into exhaust chamber P before the port R registers with passage Q. The compression chamber M contains air only and this air is considerably compressed by the descent of the working piston G, the check valve O' closing, so that when the port R of working piston G registers with passage Q the compressed air will rush through the passage Q into the right hand cylinder driving the residue of the burnt gases out

of this cylinder into the other cylinder and thence into the exhaust chamber P, thus scavenging or cleansing the cylinders of the burnt gases. The compression chamber M' through conduits L', passage D⁴ and pipe O² is connected with a suitable carburetor containing a charge of air mixed with gasoline or other combustible vapor which is drawn in by the upward movement of working piston G' through conduits L' as described. 75 When working piston G' descends the check-valve O³ closes and the charge is compressed in chamber M' until by the descent of working piston G' the port R² in said piston registers with the lower opening of passage 80 R', whereupon the compressed charge will pass from the compression chamber M' through passage R' over head G³ into explosion chamber C.

It will be observed that this passage of 85 the charge from the compression chamber M' is subsequent to the scavenging of the cylinders by the air from compression chamber M. The charge following the air is directed by a baffle plate G⁴ formed as a 90 part of head G³ to the upper part of explosion chamber C. The contents of the chambers M and M' being equal or nearly equal to the contents of the explosion chamber C, the entire portion of the burnt gases will be 95 expelled into exhaust chamber P, leaving the mixture of air or gaseous vapor nearly or quite pure.

It will also be observed that at the time of the discharge from chamber M' into explosion chamber C the slot P² connecting the interior of the cylinder with exhaust chamber P is partly closed allowing just a sufficient opening for any residue of burnt gases to escape.

The revolution of the main crank shaft F now carries working pistons G and G' upward, compressing the charge. As the working pistons G and G' move upward air is drawn in by suction past check valve O' 100 into chamber M and air and gas in a suitable mixture are drawn into chamber M' past check valve O³ as described. As working pistons G and G' descend check valves O' and O³ as described are closed so that the 105 contents of chambers M and M' may be compressed by the movement of the working pistons. In this cycle it will be observed that there is a power impulse at every downward or outward movement of the working 110 pistons from the explosion chamber, that at the end of the power impulse when nearing the extreme motion of the working pistons the exhaust from both cylinders first takes place, then a scavenging action by the air 115 compressed in chamber M and finally the introduction of a charge of air and vapor from compression chamber M'.

The above mentioned results are obtained through the use of two compression cham- 120

bers and the differential movement of working pistons G and G'. This differential movement by which the working piston G arrives at the limit of its motion a little in advance of the working piston G' and begins its return also a little in advance enables the ports to be uncovered and closed so as to obtain the successive actions above described.

10 It will be observed that there is a volume of air between the charge and the burnt gases and that the pressure of the compressed charge drives the air ahead of it and the burnt gases ahead of the air, so that if a small portion of air escapes at the exhaust chamber P no harm will be done. This enables the exhaust port between the cylinders and the exhaust chamber P and the exhaust chamber itself to be made of 15 considerable size so as to allow a complete and thorough exhaustion of the burnt gases while at the same time a pure mixture of air and gas is provided for compression and combustion.

20 25 I am aware that I am not the first to use the twin cylinder construction, and that I am not the first to use a compression chamber on the inside of a hollow piston. I am also aware that I am not the first to use a differential motion of the pistons in such 30 twin cylinder construction, but I believe myself to be the first to use the compression chambers in connection with the twin cylinder construction and to obtain the differential action of the pistons by off-setting the cylinders with reference to the crank shaft. I also believe myself to be the first to mount 35 a stationary piston directly on pipes or conduits communicating with a compression chamber, and to mount these pipes or conduits directly upon a crank case.

40 There are great advantages in this method of construction: it being simple, cheap and accessible. The pipes and conduits L and L' may be steel pipes screwed into the base plate D².

45 50 The stationary pistons I prefer to make in the form shown in Figs. 6 and 7. By the use of bolts, these pistons can be easily brought into exact alinement with the working pistons and fastened there. It is also possible by this means of adjustment, within certain limits, to increase or decrease the size of the compression chambers M and M'.

55 60 It is possible, by my improved construction, to obtain the advantages of a power impulse at every complete revolution of the crank shaft; at the same time to scavenge the cylinders by means of air under considerable compression, and to provide a pure or nearly pure mixture of air and gas for compression and explosion, and to obtain these advantages with the fewest number of moving parts.

65 It will also be noted that it is almost im-

possible for a back fire to occur with the construction which I have shown. At no time is there any direct communication between the burnt gases and the incoming "charge." The air passing from the chamber M, is 70 much cooler than the gases which it expels, and has a cooling effect upon the walls of the cylinder.

75 It will also be noted that the charge which is drawn into the chamber M', comes into this chamber at atmospheric pressure, is considerably compressed, then discharged through the passage R', and finally recompressed in explosion chamber C at the upper movement of the two working pistons, 80 thereby giving a more thorough mixture of the air and gas than can be obtained in the ordinary two cycle engine. The heating of the air by compression as the piston G' descends, also helps to make this mixture. 85

I have shown only one power unit, but it is obvious that for use in automobiles or motor boats and other constructions, two or more such power units as shown might be used. As a matter of comparison, it may be 90 said that three such twin cylinders used in an automobile would give the same torque as is now obtained in a 6-cylinder engine of the four cycle type, and at the same time avoid the use of valves, cam shafts with 95 their gears, cams and other parts necessary in such a construction.

It is also to be understood that I may use the form of compression chamber made by mounting a stationary piston inside of a 100 hollow piston and mounting said stationary piston on conduits, in connection with a single cylinder instead of a twin cylinder as previously described. In said last named construction, the compression chamber 105 would receive a charge of air and gas, and it would be delivered directly above the working piston by a passage similar to that shown in the right hand cylinder of Fig. 1.

110 It is also to be understood that while I have embodied my invention in the best form now known to me, that I do not confine myself to the exact mechanical details disclosed which may be widely varied without departing from the principles shown. 115

120 It will be observed that because of working pistons G and G' being open at the lower end and communicating directly with the crank case, the ordinary method of splash lubrication may be utilized and that through this means all working parts of the engine will be sufficiently lubricated in the easiest and most effective manner.

125 It will further be observed that by disconnecting bolts D', D', the water connections T and T' and the exhaust pipe P', the cylinders can be lifted from the crank case thereby exposing the working pistons and associated parts rendering them easy of inspection and repair. 130

- In the specification and claims where I refer to a "twin cylinder" I mean two cylinders having a common combustion head and so arranged that both cylinders may be exhausted and charges introduced into both cylinders from a port in either cylinder. Such a "twin cylinder" may be of two separate castings with connecting passages or in a single casting as shown in the drawings.
- 5 In such a twin cylinder construction the connecting-rods from the working pistons are connected to the crank shaft at substantially the same point of the crank shaft revolution and where I refer to a common driving shaft I mean to refer to such construction.
- 10
- 15

What I claim and desire to secure by Letters Patent is:

1. In an internal combustion engine, the combination of a cylinder, an exhaust in the wall of said cylinder, a hollow working piston, a stationary piston within the working piston, a compression chamber between said working piston and said stationary piston and conduits on which said stationary piston is mounted, said conduits being adapted to convey air or gas to said compression chamber.
- 20
- 25

2. In an internal combustion engine, the combination of a cylinder, a hollow working piston, a stationary piston within the working piston, a compression chamber between said working piston and said stationary piston and conduits on which said stationary piston is adjustably mounted whereby the size of the compression chamber may be varied, said conduits being adapted to convey air or gas to said compression chamber.
- 30
- 35

3. In an internal combustion engine, the combination of a cylinder, an exhaust chamber in the wall of said cylinder, a circumferential slot connecting said cylinder with said exhaust chamber, a hollow working piston adapted to uncover and cover said slot, a stationary piston within said working piston, a compression chamber between said working piston and said stationary piston and conduits on which said stationary piston is mounted, said conduits being adapted to 40 45 50 convey air or gas to said compression chamber.

4. In an internal combustion engine, the combination of a twin cylinder, a common explosion chamber for said cylinders, a working piston in each of said cylinders, a common driving shaft offset with relation to said pistons and rods connecting said shaft and said pistons, whereby said pistons are given a differential motion during the revolution of the driving shaft.
5. In an internal combustion engine, the combination of a twin cylinder, a common explosion chamber for said cylinders, a hollow working piston in each of said cylinders,
- 55
- 60

a common driving shaft offset with relation to said pistons, a stationary piston within each of said working pistons and a compression chamber between each of said working pistons and said stationary pistons.

6. In an internal combustion engine, the combination of a twin cylinder, a common explosion chamber for said cylinders, a hollow working piston in each of said cylinders, a common driving shaft offset with relation to said pistons, a stationary piston within each of said working pistons, a compression chamber between each of said working pistons and said stationary pistons and conduits on which said stationary pistons are mounted, said conduits being adapted to convey air or gas to said compression chambers.

7. In an internal combustion engine, the combination of a twin cylinder, a common explosion chamber for said cylinders, a hollow working piston in each of said cylinders, a common driving shaft for said pistons, a stationary piston within each of said working pistons, a compression chamber between each of said working pistons and said stationary pistons and conduits on which said stationary pistons are adjustably mounted whereby the size of the compression chamber may be varied, said conduits being adapted to convey air or gas to said compression chambers.

8. In an internal combustion engine, the combination of a twin cylinder, a common explosion chamber for said cylinders, a hollow working piston in each of said cylinders, a common driving shaft for said pistons, a stationary piston within each of said working pistons, a base plate, conduits mounted in said base plate and in turn supporting the stationary pistons and air and gas inlets in the base plate connecting with said conduits.

9. In an internal combustion engine, the combination of a twin cylinder, a common explosion chamber for said cylinders, passages for air and gas through the walls of said cylinders, a hollow working piston in each of said cylinders, ports in said working pistons adapted to register with said passages for air and gas, a stationary piston within each of said working pistons, a compression chamber between each of said working pistons and said stationary pistons and conduits on which said stationary pistons are mounted, said conduits being adapted to convey air or gas to said compression chambers.

10. In an internal combustion engine, the combination of a cylinder, a hollow working piston open at one end within said cylinder, a stationary piston within said working piston, a compression chamber between said working piston and said stationary piston,

100

105

110

115

120

125

conduits on which said stationary piston is mounted, said conduits being adapted to convey air or gas to said compression chamber and a crank case upon which said conduits are mounted.

11. In an internal combustion engine, the combination of a cylinder, a hollow working piston open at one end within said cylinder, a stationary piston within said working piston, conduits on which said stationary piston is mounted, a crank case in which said conduits are mounted and air and gas inlets in said crank case connecting with said conduits.

12. In an internal combustion engine, a twin cylinder, a hollow working piston in each of said cylinders, a common explosion chamber for said cylinder, passages through the walls of said cylinder for the exhaust, air scavenging charge and explosive mixture charge respectively, ports in said working pistons adapted to register with the air scavenging charge passage and explosive mixture charge passage respectively, said exhaust, air scavenging control and explosive mixture control being brought into action successively by the movement of the working pistons which successively uncover and cover the openings in the said exhaust, air scavenging passage and explosive mixture passage.

13. In an internal combustion engine, a twin cylinder, a common explosive chamber for said cylinder, a hollow working piston in each of said cylinders, an exhaust, air scavenging passages and explosive mixture passage through the walls of said cylinder, and ports in said working pistons adapted to register with said air scavenging passage and explosive mixture passage, one of said working pistons being adapted to uncover and cover the exhaust and to introduce the air scavenging charge and the other of said working pistons being adapted to introduce the explosive mixture charge.

14. In an internal combustion engine, a twin cylinder, a common explosion chamber in said cylinder, an exhaust from said cylinder, a hollow working piston in each of said cylinders, an air scavenging passage through the wall of said cylinder controlled by the movement of one of said working pistons and brought into operation while the exhaust is open and after the burnt charge has passed off and an explosive charge passage through the wall of said cylinder controlled by the movement of the other of said working pistons and brought into action upon the closure of the air scavenging passage.

15. In an internal combustion engine, the combination of a twin cylinder, two working pistons, two compression chambers, an exhaust port, and ports in the cylinders and

working pistons adapted to register so that the movement of the pistons will cause in succession the discharge of the burnt gases, the scavenging of air and the introduction of a charge of air and gas for subsequent compression and explosion.

16. In an internal combustion engine, the combination of a twin cylinder, two working pistons, stationary pistons in the working pistons, two compression chambers, an exhaust port, and ports in the cylinders and working pistons so arranged that the movement of the working pistons will cause in succession the discharge of the burnt gases, the scavenging of the cylinders by air and the introduction of a charge of air and gas for subsequent compression and explosion.

17. In an internal combustion engine, the combination of a twin cylinder, two working pistons, stationary pistons in the working pistons, two compression chambers, an exhaust port, ports in the cylinders and working pistons and a crank shaft connected to the working pistons, said crank shaft being offset so as to cause a differential movement of said pistons adapted to cause in succession a discharge of the burnt gases, the scavenging of the cylinders by air and the introduction of a charge of air and gas for subsequent compression and explosion.

18. In an internal combustion engine, the combination of a cylinder, an explosion chamber, a piston and a compression chamber adjustable in size within said piston, said compression chamber lying wholly above the connection of the piston with the connecting-rod, whereby a relatively high degree of compression may be obtained.

19. In an internal combustion engine, the combination of twin cylinders, two compression chambers, an exhaust port and inlet ports with differentially moving pistons forming one side of said compression chambers and in their movement operating to control said ports.

20. In an internal combustion engine, the combination of twin cylinders, a common explosion chamber, a piston in each of said cylinders and means in each of said pistons adapted to form one end of a compression chamber, the other end of the compression chamber being formed by the piston.

21. In an internal combustion engine, the combination of twin cylinders, a common explosion chamber, a piston in each of said cylinders, a common driving shaft offset with relation to said pistons, and a compression chamber within each of said pistons, said compression chambers lying wholly above the connection of said pistons with their respective connecting-rods.

22. In an internal combustion engine, the combination of a twin cylinder, a piston in each of said cylinders, a common driving

shaft offset with relation to said pistons, a compression chamber lying wholly within each of said pistons and means by which the reciprocation of the pistons will alternately draw in and compress a charge of air or gas.

23. In an internal combustion engine, the combination of a twin cylinder with a working piston in each of said cylinders, a common driving shaft offset with relation to said 10 pistons, and a fixed piston adapted to co-operate with each of said working pistons to obtain a high compression of a charge of air or gas.

24. In an internal combustion engine, the combination of a twin cylinder with a working piston in each of said cylinders and an adjustable fixed piston adapted to co-operate with each of said working pistons to obtain a high compression of a charge of air 20 or gas.

25. In an internal combustion engine, the combination of a twin cylinder, a common explosion chamber, a piston in each of said cylinders, a common driving shaft offset 25 with relation to said piston, a separate compression chamber co-operating with each of said pistons, an exhaust port and inlet ports, said pistons being adapted to be operated differentially to control said exhaust and 30 inlet ports.

26. In an internal combustion engine, the combination of a twin cylinder, a common explosion chamber, a piston in each of said cylinders, a separate compression chamber co-operating 35 with each of said pistons, an exhaust port and inlet ports, said pistons being adapted to be operated differentially to close said exhaust port, either wholly or in part, before opening the inlet port for the 40 gaseous charge.

27. In an internal combustion engine, the combination of a twin cylinder, a common explosion chamber, a piston in each of said cylinders, a compression chamber co-operating 45 with each of said pistons, an exhaust port and inlet ports, one of said pistons being adapted to control the exhaust port and the other the gas inlet port, and means for operating the pistons differentially whereby 50 the exhaust port is closed, in whole or in part, before the opening of the gas inlet port.

28. In an internal combustion engine, the combination of a twin cylinder, a piston for 55 each cylinder, an exhaust port and air and gas inlet ports, said pistons being adapted to move differentially and to control the ports so as to cause in succession the opening of the exhaust port, the opening of the air 60 inlet port, the closing of the exhaust port, in whole or in part, and the opening of the gas inlet port.

29. In an internal combustion engine, the combination of a twin cylinder, a piston for

each cylinder, a compression chamber co-operating with each piston, an exhaust port, and air and gas inlet ports from said compression chambers, said pistons being adapted to move differentially and to control the ports so as to cause in succession the opening of the exhaust port, the opening of the air inlet port, the closing of the exhaust port, in whole or in part, and the opening of the gas inlet port.

30. In an internal combustion engine of 75 the two-cycle type, the combination of pistons and compression chambers so co-operating with each other as to cause in succession the exhausting of the burnt gases, the scavenging of the residue of the burnt gases, the 80 closing of the exhaust opening, in whole or in part before the introduction of a fresh charge, the introduction of a fresh charge and the compression of said charge for subsequent firing.

31. In an internal combustion engine of 85 the two-cycle type, the combination of a crankshaft, connecting rods and pistons as the only moving parts, and an exhaust port and inlet ports, said pistons being adapted 90 to be operated differentially to control said exhaust and inlet ports, in co-operation with compression chambers so arranged as to cause in succession the exhausting of the burnt gases, the scavenging of the residue 95 of burnt gases, the closing of the exhaust opening, in whole or in part before the introduction of a fresh charge, the introduction of a fresh charge and the compression of said charge for subsequent firing.

32. In an internal combustion engine of 100 the two-cycle type, the exhaust and inlet ports of which are controlled solely by the movement of the piston or pistons, means for closing the exhaust port in whole or in part before the opening of the inlet port for the fresh charge.

33. In an internal combustion engine, the combination of a cylinder, a piston open at one end, a crank shaft, a connecting rod between said piston and crank shaft and an adjustably mounted fixed piston located between the top of the first named piston and the point of connection between said piston and the connecting rod.

34. In an internal combustion engine, the combination of a cylinder, a piston open at one end, a crank shaft, a connecting rod between said piston and crank shaft, an adjustably mounted fixed piston located between the top of the first named piston and the point of connection between said piston and the connecting rod and supporting means for the fixed piston out of the path of the connecting rod.

35. In an internal combustion engine, the combination of a plurality of cylinders, a piston open at one end in each of said cyl-

inders, a crank shaft, a connecting rod between each of said pistons and the crank shaft and a normally fixed piston in each of said cylinders located between the top of 5 the first named piston therein and the point of connection between said piston and the connecting rod.

36. In an internal combustion engine, the combination of a plurality of cylinders, a 10 piston open at one end in each of said cylinders, a crank shaft, a connecting rod between each of said pistons and the crank shaft and an adjustably mounted fixed piston in each of said cylinders located between 15 the top of the first named piston therein and the point of connection between said piston and the connecting rod.

37. In an internal combustion engine, the combination of a plurality of cylinders, a 20 piston open at one end in each of said cylinders, a crank shaft offset with relation to said piston, a connecting rod between each of said pistons and the crank shaft, a normally fixed piston in each of said cylinders 25 located between the top of the first named

piston therein and the point of connection between said piston and the connecting rod and supporting means for each of said fixed pistons out of the path of the connecting rod.

30

38. In an internal combustion engine, the combination of a plurality of cylinders, a piston open at one end in each of said cylinders, a crank shaft, a connecting rod between each of said pistons and the crank shaft, an adjustably mounted fixed piston in each of said cylinders located between the top of the first named piston therein and the point of connection between said piston and the connecting rod and supporting means 35 for each of said fixed pistons out of the path of the connecting rod.

35

In testimony whereof I have signed this specification in the presence of two subscribing witnesses.
